UNITED STATES PATENT OFFICE.

EDWARD ELMER SHIVELY, OF DETROIT, MICHIGAN.

PERMUTATION LOCK.

Application filed January 25, 1922. Serial No. 531,565.

To all whom it may concern:

Be it known that EDWARD E. SHIVELY, a citizen of the United States, residing at Detroit, in the county of Wayne and State of Michigan, has invented certain new and useful Improvements in Permutation Locks, of which the following is a specification.

This invention relates to improvements in locks and particularly in permutation locks 10 for safes and the like.

The details and objects of the invention will appear as described in connection with the accompanying drawings and herein-after set forth and claimed.

15 In the drawings forming a part of this specification, like characters of reference are used to designate the same parts in the several figures, in which,

Figure 1 is an elevation of the front of a 20 safe, showing the general arrangement of various parts,

Figure 1^a is a similar elevation on an enlarged scale showing elements of a lock in accordance with this invention in their 25 proper relationship in a portion of a safe door,

Figure 2 is an elevation disclosing the mechanism of the lock uncovered in the back of the safe door as disclosed in Figure 1^a,

30 Figure 3 is a horizontal section of the door and lock taken on line 3—3 of Figure 1^a, the lock being shown in plan and parts thereof being omitted in this figure so as to 35 avoid confusion.

Figure 4 is a vertical sectional view taken on line 4—4 of Figure 2.

Figure 5 discloses a side and an edge elevation of the base plate of the bolt member 40 of the lock,

Figure 6 is an elevation of the bolt and its carrying plate,

Figure 7 discloses elevations of one of the permutation tumblers, and

45 Figures 8 to 14 inclusive disclose detail views of various other parts of the lock.

The lock comprising the subject matter of this invention is represented as being mounted in the door of a safe 20, and as seen 50 in the front views of the safe, includes a combination lock 21, key lock 22, and operating handle 23.

The combination lock 20 includes the knob 24, dial ring 25, tumblers 26 and 27, change 55 wheel 28 and driver 29, as best shown in

Figures 2 and 3. The permutation members also have a tumbler 30, shown in the detail views in Figure 7; this tumbler has a projection 31 for operating a plunger as will hereinafter appear. The tumbler members 60 26, 27 and 28, are provided with slots such as 32 in the change wheel 28 and tumbler 26 (see Figure 13), which, when the tumblers have been turned to the correct combination so that the slots line up in the required manner will receive a projection 33 of the bolt member so that the bolt may be retracted for opening the safe.

The bolt member comprises a sliding plate 34 carrying the projection 33 and a bolt bar 35 with the bolts 36 which project through apertures 37 in the safe door, and a spring 34' is provided for retracting said member. As shown in Figures 2, 3 particularly, and 6, 70 the projection 33 is tapered outwardly toward the change wheel 28 so that it cannot be used as a feeler for the permutation tumblers 26 and 27 which have to be set first.

A base plate 38 upon which plate 34 is 75 mounted is secured to the safe door by means of four machine screws 39; it is provided with a tapped lug 40 for receiving a stud screw 41 which passes through a slot 42 in the bolt plate for guiding it. There are recessed lugs 43 and 44 extending from the 80 base plate which carry spring pressed pins 45 and 46 that normally project through apertures 47 and 48 in the bolt plate when the bolts 36 are projecting outwardly from the safe door in their locking position. The 85 base plate also has a lug 49 for receiving the stem 50 of the operating handle 23; this stem on its inner end is provided with a gear 51 which meshes with a rack 52 on the bolt plate and is adapted to reciprocate the 90 same, when it is free in the customary manner.

Before the bolt plate can be moved for retracting the bolts 36, it is first necessary to force the pins 45 and 46 back into the lugs 100 and out of the apertures 47 and 48 so as to allow it to slide freely. The first pin is moved by means of the end of a key 53 passing through the lock 22, and pin 46 is moved by means of the projection 31, on the tumbler 105 30.

Lock 22 includes the drum 54 for receiving key 53 and spring-pressed tumblers 55, and back plate 56 which are of the usual construction. The back plate 56 has an ex- 110

tension 57 having a pin and slot connection 58 with the bolt plate 34; the slot is arranged so as to extend cross-wise of the bolt plate so that there may be play in the connection of the pin and slot lengthwise of the slot but not in the direction of the reciprocation of the bolt plate. Thus when the proper key 53 for releasing tumblers 55 is inserted the reciprocation of bolt plate 34 10 may be effected by means of the operating handle 23, and when the key is withdrawn the tumblers 55 will lock the drum from turning thereby preventing the reciprocation of the bolt plate. There are also a pair of projecting lugs 59 on the back plate which carry a pivoted lever 60 having a spring 61 connected at 62 and with the base extension 63 which carries the lock tumblers and forms a bearing for the drum. This 15 spring 61 holds the end 62 of the lever normally against the back plate. However when key 53 is properly positioned in the drum 54, its end 53' will turn the lever on its pivot against the tension of spring 61 and the end 64 of this lever will cooperate with the projection 65 of a lever 66 for forcing pin 45 down so as to disengage aperture 47 in the plate. It will be noted that lever 60 is maintained in its releasing position, bearing on lever 66, in any position of the bolt plate 34, and that after the pin 45 has been disengaged from the aperture, and the plate has been moved the end of the pin is maintained in its depressed position 20 by its sliding engagement with the plate 23, and is held there independent of the lock and key. Lever 66 is pivoted in lugs 67 extending from the bolt plate, and its end 68 has a set screw 69 for adjusting it and for holding lever 66 so as to keep pin 45 out of the aperture 47 in the plate when desired. 25 Pin 46 is moved out of its aperture 48 in the sliding plate in a similar manner by a projection 70' on a lever 70 (see Figure 12), pivoted in lugs 71 extending from the bolt plate; this lever has a set screw 72 which operates in the same manner as set screw 69. A bracket 73 (Figure 8) is secured to the base plate 38 and carries a lever 74 (Figure 9) pivoted thereto at 74' and a plunger 75 (Figure 11). The lever 74 has an arm 76 which is engaged by the end 77 of plunger 75 and a projection 78 on its other arm for engaging lever 70. A guide member 79 (Figure 10) is also secured to the base plate along the side of the bracket 73 and its bifurcated end 80 is adapted to receive a portion of the head 81 of the plunger 75. The various elements are 30 shown assembled in the elevation, Figure 2, and it will be seen that when the projection 31 on the tumbler 30 engages the head 81 of the plunger, the various levers will be acted upon and move the pin 46 so as to 35 disengage the bolt plate 34.

A protecting cover 82, as shown in Figures 1, 1^a and 14, is preferably positioned at the end of the drum 54 for closing the key lock. This cover comprises a base member 83 which is secured to the door of the safe in a position surrounding the exterior flange 85 of the drum 54, and a plate 86 pivoted thereto and having a spring 87 for closing it when the key is withdrawn.

In operation, tumbler 30 is turned so that the projection 31 will release the pin 46 from the bolt plate and the tumblers 26, 27 and change wheel are set to the proper combination in the usual manner in order to aline the slots 32 for receiving the projection 33 on the bolt plate. After key 53 is inserted so as to release the pin 45, the bolt 36 may then be retracted by turning the operating handle 23, or by means of the spring 34'. It will be seen that in the operation of the tumblers that the tumbler 30 is the first to be positioned, then tumblers 26 and 27 and the change-wheel 28 in order; thus it would be impossible to use the tapered projection 33 as a feeler for lining the tumblers.

Obviously, either pin 45 or 46 and the respective operating mechanism may be omitted as in some constructions the key lock 22 may prove objectionable, therefore the pin 46 and permutation members alone may be employed. Likewise, any number of such pin locks may be used in the lock, with key locks or permutation tumblers for operating them. In case the combination lock for releasing the sliding bolt members is blown off, the bolts 36 still cannot be retracted since the releasing plunger 75 is forced out by its spring 88 without releasing the pin 46.

Many other advantages of the herein described invention will readily suggest themselves to those skilled in the art to which it appertains.

Having thus set forth the invention, it is not desired to have it confined closely to the specific disclosures in the drawings, it being understood that changes may be made in form, proportion and organization of its various parts without departing from the spirit of the invention as indicated by the following claims.

What is claimed as the invention, and is desired to be secured by Letters Patent is:

1. In a lock including a bolt member mounted on a sliding plate adapted to be reciprocated for positioning the bolt member in locking and retracted positions, an operating member for reciprocating said member, pin members normally projecting through apertures in the sliding bolt plate so as to hold the same against movement, a key, a key lock having means engaging with said sliding bolt plate, means extending therefrom for displacing one of said pins

40

from said plate when the key is positioned in the key lock, a permutation lock, and means for displacing the second pin from said plate including one of the tumblers of said permutation lock.

45

2. In a lock including a bolt member mounted on a sliding plate adapted to be reciprocated for positioning the bolt member in locking and retracted positions, an operating member for reciprocating said member, a pin member normally projecting through an aperture in the sliding bolt plate so as to hold the same against movement, a key, a key lock having means engaging 50 with said bolt plate with means for displacing said pin from the aperture in the plate when the key is positioned in the lock.

55

3. In a lock including a bolt member mounted on a sliding plate adapted to be reciprocated for positioning the bolt member in locking and retracted positions, an operating member for reciprocating said member, a key, a key lock including a rotatable drum and tumblers for locking the same, 60 and a connection between the lock drum and said sliding bolt plate for preventing the same from being reciprocated except when the key is positioned in the lock for releasing the tumblers.

65

30 4. In a lock including a bolt member mounted on a sliding plate adapted to be reciprocated for positioning the bolt member in locking and retracted positions, an operating member for reciprocating said member, a pin member normally projecting through an aperture in the sliding bolt plate so as to hold the same against movement, a permutation lock, and means for displacing 70

said pin from said plate including a tumbler of the permutation lock.

5. In a lock including a bolt member mounted on a sliding plate adapted to be reciprocated for positioning the bolt member in locking and retracted positions, an operating member for reciprocating said member, a projection on said sliding bolt plate, a permutation lock the tumblers of which are adapted to receive said projection when the lock has been set to the required combination, a pin member normally projecting through 55 an aperture in the sliding bolt plate so as to hold the same against movement, and means for displacing said pin member from the aperture in said plate whereby it may be reciprocated to a position with said projection within said tumblers.

6. In a lock including a bolt member mounted on a sliding plate adapted to be reciprocated for positioning the bolt member in locking and retracted positions, an operating member for reciprocating said member, a projection on said sliding bolt plate, a permutation lock the tumblers of which are adapted to receive said projection when the lock has been set to the required combination, a key, a key lock including a rotatable drum and tumblers for locking the same, 65 and a connection between the lock drum and said sliding bolt plate for preventing the same from being reciprocated except when the key is positioned in the lock for releasing the tumblers.

In testimony whereof I affix my signature.

EDWARD ELMER SHIVELY.
